UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CAN-CLOSING MACHINE.

Application filed September 14, 1925. Serial No. 56,271.

The present invention relates to can closing machines and is embodied in an apparatus similar, in many respects, to that of my co-pending application of even date herein with, bearing Serial No. 56,272.

Both the present machine and that of my co-pending application are adapted to operate upon containers of the barrel type, in which the ends are extended beyond the 10 seams by which they are attached to the container body, making it therefore impossible to use the ordinary type of double seaming machine in which the seam is backed up during the seaming operations by means of 15 a chuck entering a counter-sunk end. The machine of the other application is adapted for attaching the cover to the container body, and the present machine is particularly adapted for applying the bottom end, 20 which is the first to be attached.

The principal object of the invention is to provide an improved supporting means for the can, including an element for backing up the seam during operation of the seaming rollers. The invention resides primarily in said supporting means and the mechanism 25 for operating the same and in the combination of parts as set out in the appended claims.

30 Numerous other objects and advantages of the invention will be apparent as it is better understood from the following description, which, taken in connection with the accompanying drawings, discloses a preferred embodiment thereof.

Referring to the drawings,

Figure 1 is a perspective view of a double seaming machine in which my invention is embodied;

40 Fig. 2 is a sectional and plan view thereof, taken just above the seaming mechanism; and

Fig. 3 is a detail showing the can support and backing up member, or anvil, in its relation to one of the seaming rollers, the can 45 being shown in position for seaming and being partially broken away for better illustration.

Upon said drawings, illustrating the best 50 manner in which I have thus far contemplated applying the principles of my invention, the reference character 11 indicates a column, or standard arising from a base 12, said column having a drive shaft 13 journaled therein at its upper end and carrying

a drive pulley 14, which is adapted to be driven by means of a suitable belt from any available source of power. Said shaft carries at its inner end a bevel gear 15, meshing with a similar gear 16 upon a vertical 60 shaft 17, journaled in bearings 18 and 19 formed in forward extensions 21 and 22 of said standard 11. Said shaft 17 carries at its lower end a chuck 23, adapted to engage the end of the can to rotate the latter during the seaming operation.

The seaming mechanism is, generally, similar to that described in detail in my co-pending application and is not shown in detail here since it forms no part of the present 70 invention. A bracket, or guideway, 24 extends laterally from the standard 11 and carries a sliding block 25, adapted to be adjusted to properly position the seaming mechanism for cans of different diameter by 75 means of a threaded rod 26, provided with a handle 27 for manual operation. The first, second and third operation seaming rollers, which I have indicated, respectively, by the reference characters 28, 29 and 31 in Fig. 2 80 of the drawings, are carried by a disk or turret 32, rotatably mounted upon an axis 33 and adapted to be turned about said axis by means of a handle 34, adapted to be manipulated by the operator.

Referring now to the can supporting means, it will be seen that the can 35, with the bottom end 36 applied thereto and the opposite end open, is supported upon a rotatable support plate 37, which is carried 90 at the upper end of a bar 38, pivoted at 39 to a rod 41, which is slidably mounted in a bracket 42 extended from the column 11. Said rod is adapted to be raised and lowered by means of an arm 43, having its forward 95 end engaged in a slot 44 in the lower end of said rod, said arm being pivoted to the frame at 45 and connected by means of a rod 46 with a foot lever 47 pivoted at 48 and having a foot pedal 49 at the forward end thereof, said lever being held in centered position by guides 51 arising from the base 12. The bar 38 has studs 52 projecting from the opposite sides thereof and disposed in cam slots 53 formed in a bifurcated bracket 100 54 extending forwardly from the upright 11, above the bracket 42, this construction being such that the bar 38 and support plate 37 fall forwardly to the position shown in dotted lines in Fig. 1 when the foot lever is 110

raised and are brought to the upright position shown in full lines in Fig. 1 when said foot lever is depressed. It will be apparent that when in the dotted line position, a can 5 may be positioned or removed, and when raised to the full line position, said can may be engaged by the chuck 23 and rotated to perform the seaming operation.

Secured to the top of the support plate 37 10 is a backing-up member, or anvil, 55, which has a flange 56 at the bottom thereof, over which the open end of the can is adapted to engage, the upper end of said anvil having a beveled shoulder 57 thereon adapted 15 to fit within the can end 36 and to back up the seam 58 during the operation of the seaming rollers. The can is thus firmly supported and the parts entering into the seam are held in proper relationship to effect accurate and tight seaming, and provision is 20 made for quickly and easily removing and positioning the cans.

It is thought that the invention and many of its attendant advantages will be understood from the foregoing description, and it will be apparent that various changes may be made in the form, construction and arrangement of the parts without departing from the spirit and scope of the invention, or 25 sacrificing all of its material advantages, the form hereinbefore described being merely a preferred embodiment thereof.

I claim:

1. A can closing machine, comprising a 35 frame, a can support, a chuck adapted to clamp a can and positioned end onto said support, seaming mechanism carried by said frame and positioned adjacent said support, means for effecting relative rotary movement of the can and seaming mechanism, and 40 an element on said support over which the can is adapted to be positioned and which at the seaming line is of substantially the same diameter as the interior of the can 45 and is adapted to back up a seam, securing the end to the can body intermediate the ends of the finished can.

2. A can closing machine, comprising a frame, a can support, a chuck adapted to 50 clamp a can and positioned end onto said support, seaming mechanism carried by said frame and positioned adjacent said support, means for effecting relative rotary movement of the can and seaming mechanism, and 55 an element on said support over which the can is adapted to be positioned and which is adapted to back up a seam, securing the end to the can body intermediate the ends of the finished can, said support being movable away from seaming position and from 60 under the top chuck to permit positioning and removal of the cans.

3. A can closing machine, comprising a frame, seaming mechanism supported there- 65 by, means for supporting a can and positioned

end in position to be operated upon by said mechanism, said means including a member pivoted to be movable from under the top chuck provided with an anvil over which the can is adapted to be placed and which is adapted to back up the seam on the inside thereof during the seaming operation, and means for effecting relative rotary movement of the can and seaming mechanism. 70

4. A can closing machine, comprising a frame, seaming mechanism supported thereby, means for supporting a can and positioned end in position to be operated upon by said mechanism, said means including a pivoted member provided with an anvil over 75 which the can is adapted to be placed and which is adapted to back up the seam on the inside thereof during the seaming operation, and means for effecting relative rotary movement of the can and seaming mechanism, said pivoted member having one position wherein the can may be positioned upon or removed from said anvil and another position holding the can in proper relation 80 for seaming. 85

5. A can closing machine, comprising a frame, seaming mechanism supported thereby, means for supporting a can and positioned end in position to be operated upon by said mechanism, said means including a pivoted member provided with an anvil over 90 which the can is adapted to be placed and which is adapted to back up the seam on the inside thereof during the seaming operation, means for effecting relative rotary movement of the can and seaming mechanism, said pivoted member having one position wherein the can may be positioned upon or removed from said anvil and another position holding the can in proper relation 95 for seaming. 100

6. A can closing machine, comprising a frame, seaming mechanism supported thereby, means including a pivoted member for supporting a can and positioned end in position to be operated upon by said mechanism, means for raising and lowering said member, and a cam acting upon said member to move the same laterally during the raising and 105 lowering movement thereof, said can and seaming mechanism having relative rotary movement. 110

7. A can closing machine, comprising a frame, seaming mechanism supported thereby, means for supporting a can and positioned end in position to be operated upon by said mechanism, said means including a member pivoted to be movable from under the top chuck provided with an anvil over which the can is adapted to be placed and which is adapted to back up the seam on the inside thereof during the seaming operation, means for centering the opposite end of the can, and means for effecting relative rotary 125 130

movement of the can and seaming mechanism.

8. A can closing machine, comprising a frame, seaming mechanism supported thereon by, means for supporting a can and positioned end in position to be operated upon by said mechanism, said means including a pivoted member provided with an anvil over which the can is adapted to be placed and which is adapted to back up the seam on the inside thereof during the seaming operation, means for effecting relative rotary movement of the can and seaming mechanism, means for raising and lowering said pivoted member, and a cam acting upon said mem-

ber to move the same laterally, during the raising and lowering movement thereof, to accessible position for positioning or removal of a can.

9. A can closing machine having in combination, a rotatable can support, a chuck adapted to clamp a can and positioned end on to said support, seaming rolls positioned adjacent said support and movable against the cans, means for rotating said chuck, an anvil element on said support, and a pivotal joint below said support on which said support and anvil can turn out from under the upper chuck. 20 25

JOHN M. HOTHERSALL.
